UNITED STATES PATENT OFFICE.

ANDRÉ JOSEPH ICARD, OF TOULON, FRANCE.

AUTOMATIC BLOCK SYSTEM FOR PREVENTING COLLISIONS ON RAILWAYS.

1,094,906.

Specification of Letters Patent. Patented Apr. 28, 1914.

Application filed March 21, 1912. Serial No. 685,242.

To all whom it may concern:

Be it known that I, ANDRÉ JOSEPH ICARD, a citizen of the Republic of France, residing at Toulon, France, have invented certain 5 new and useful Improvements in Automatic Block Systems for Preventing Collisions on Railways, of which the following is a specification.

This invention relates to automatic block 10 systems for preventing collisions between railway trains, and has for its object to provide a single construction of a device of this kind, which will be efficient in operation and will not get out of order.

15 In the accompanying drawing Figures 1, 1^a and 1^b are complementary figures together forming a side view of a portion of a railway provided with my invention, and Figs. 2, 2^a and 2^b are complementary figures together 20 forming a plan thereof.

The railway track is divided into sections or blocks of suitable length, and at the beginning of the sections track levers are provided, the track lever *a* at the beginning of 25 the initial section and the track lever *a'* at the beginning of any succeeding section; while at the end of the terminal section a terminal track lever *a²* is provided.

Each track lever has an upright portion, 30 pivoted below the track rail, and a curved track portion extending above the track rail for contact with the train wheel.

At a suitable distance, in which a train 35 may be conveniently stopped before reaching respective track levers, guide frames *b*, *b'* and *b²* are provided, in which vertically move the respective stop-pins *c*, *c'* and *c²* actuated by the respective lifting levers *d*, *d'* and *d²* operatively connected with the lower 40 free ends of the respective track levers *a*, *a'* and *a²*, as will be explained.

The levers *d*, *d'* and *d²* are respectively mounted on rock shafts *e*, *e'* and *e²* respectively carrying upwardly pointing arms *f*, *f'* and *f²*. The arm *f* is connected by the link *g* with the lower end of the track lever *a*. The arm *f'* is connected by the long link *g'* to the free upper end of the pivoted lever *h'* in turn connected by the oblique link *i'* with the lower end of the track lever *a'*. The arm *f²* is connected by the long link *g²* to the upper free end of the centrally pivoted lever *h²*, the lower free end of which is connected by the lower link *i²* to the lower 55 free end of the track lever *a²*.

Springs *j*, *j'* and *j²* normally hold the re-

spective levers *d*, *d'* and *d²* in their lower position, and thereby hold the track levers in upper position.

Hooks *k*, *k'* and *k²*, pivoted at their lower 60 ends, are adapted to engage over the free end of the track levers *a*, *a'* and *a²*, respectively, and are normally held in engaging position, by the respective springs *l*, *l'* and *l²*.

The hooks *k* and *k'* are adapted to be 65 moved to disengaging position by the depression of the succeeding track levers *a'* and *a²*, respectively, as follows: The free end of the pivoted lever *m* engages the hook *k* and is connected by the link *n* to one free 70 end of the pivoted lever *o*, the other free end of which is connected to link *g'* above mentioned. The hook *k'* is engaged by the free end of the pivoted lever *m'*, which lever is connected by the link *n'* to the pivoted lever *o'* in turn connected by the link *p'* to one free end of the lever *q'*, the other free end of which is connected to the link *g²* above mentioned.

Each locomotive is provided with a lever 80 *r*, located just behind the wheel guard *s*, of a sufficient length to strike against the stop-pins *c*, *c'* and *c²*. This lever, when thus struck, operates, by means of a special apparatus, the Westinghouse brake, the steam 85 intake and the locomotive whistle. This operation is effected only when the line is closed and the stop-pin raised. Since many kinds of locomotives are used, it is thought unnecessary to describe in detail this special 90 apparatus.

The operation of the system is as follows: The line being clear, all levers *d*, *d'* and *d²* and the pins *c*, *c'* and *c²* are in depressed 95 position and the track levers are in raised position. If now a train passes from the point 1 (at the left of Fig. 1) toward the point 2 (at the right of Fig. 1^b), the wheel will depress the track lever *a*, which will be caught and held in depressed position by the hook *k*, whereby the pin *c*, raised by the depression of the lever *a*, will be held in raised position. The pin *c* will thus be held in raised position until the train has reached and depressed the next track lever *a'*, whereupon the pin *c'* will be raised and the track lever *a*, and with it the pin *c*, will be released by movement of the hook *k*. In like manner, the succeeding track levers will be depressed and corresponding pins raised to be in turn 110 released when a train enters the next succeeding block. If by chance, a block be

occupied by a train, and therefore the pin c , c' or c'' at the entrance end of such block be raised, another train entering such block, will engage the raised pin with the actuating lever r , thus actuating the brake, the steam-intake and the whistle, bringing the train to a stand still.

10 The apparatus controlling the sections may be placed either between or outside of the rails.

Moreover I reserve the right to introduce into this new system any changes capable of increasing the safety of traveling which may actually result from my invention.

15 I claim as my invention:—

1. In an automatic system for preventing collisions, the combination of track levers each having an approximately upright centrally fulcrumed portion and a curved tread portion extending above the rail track; vertical guide frames associated with the respective track levers; a stop pin in each guide frame; right angle levers each having a horizontal engaging portion under one of the stop pins, and a vertical arm; rods connecting the upper ends of the vertical arms with the lower ends of said upright portions respectively; spring pressed clamping hooks adapted to engage over the ends of the respective tread portions; and a rod connecting each track lever with the hook associated

with the preceding track lever for releasing the hook when a succeeding track lever is depressed.

2. In an automatic system for preventing collisions, the combination of track levers each having an approximately upright centrally fulcrumed portion and a curved tread portion extending above the rail track; vertical guide frames associated with the respective track levers; a stop pin in each guide frame; right angle levers each having a horizontal engaging portion under one of the stop pins, and a vertical arm; rods connecting the upper ends of the vertical arms with the lower ends of said upright portions respectively; spring pressed clamping hooks adapted to engage over the ends of the respective tread portions; a rod connecting each track lever with the hook associated with the preceding track lever for releasing the hook when a succeeding track lever is depressed; and springs depressing said horizontal portions; all of said levers and rods being without counterweights.

50 In testimony whereof I affix my signature in presence of two witnesses.

ANDRÉ JOSEPH ICARD.
